UNITED STATES PATENT OFFICE.

RALPH S. TYLER, OF CLEVELAND HEIGHTS, OHIO, ASSIGNOR TO THE CHANDLER AND PRICE COMPANY, OF CLEVELAND, OHIO, A CORPORATION OF OHIO.

PRINTING PRESS.

Application filed January 22, 1921. Serial No. 439,083.

To all whom it may concern:

Be it known that I, RALPH S. TYLER, a citizen of the United States, and a resident of Cleveland Heights, county of Cuyahoga, 5 and State of Ohio, have invented a new and useful Improvement in Printing Presses, of which the following is a specification, the principle of the invention being herein explained and the best mode in which I have 10 contemplated applying that principle, so as to distinguish it from other inventions.

The present improvements, relating, as indicated, to printing presses, have more particular regard to platen printing presses of 15 the familiar Gordon type, in which a pair of inking rolls, which are made of a special, more or less resilient, composition, are mounted in a reciprocating carriage, and receive the ink from a suitable fountain or 20 like device disposed at the upper limit of such carriage's travel. In the course of the downward movement of the carriage the rolls first pass over a disk which assists in distributing the ink uniformly across the 25 same, and then over the form to which the ink requires to be transferred prior to printing therefrom. Such form is set in a bed, and the rolls are held so as to contact with such form under proper pressure by means 30 of an integral track on either side of the form with which the exposed metal ends of the rolls engage.

It is found in practice that the composition 35 that forms the body of the roll has a tendency to change its diameter, under conditions of use, with the result that after a time the rolls no longer contact with the form under the proper pressure so as to apply the ink in the right amount and evenly there- 40 over. The object of the present invention, accordingly, is to provide an adjustable track wherewith the rolls may thus engage in passing over the form, the adjustment being of such a character that the contacting 45 pressure of the rolls with the form may be gaged to suit the varying diameter of the rolls either initially or after use.

To the accomplishment of the foregoing and related ends, the invention, then, consists of the means hereinafter fully described 50 and particularly pointed out in the claims, the annexed drawing and the following description setting forth in detail certain mechanism embodying the invention, such 55 disclosed means constituting, however, but

one of various mechanical forms in which the principle of the invention may be used.

In said annexed drawing:—

Fig. 1 is a broken side elevation of a Gordon printing press, showing my improved 60 construction of adjustable track incorporated therein; Fig. 2 is a central section through one such track; and Fig. 3 is partly a side elevation of the latter and partly a section at right angles to that of Fig. 2, the 65 plane of such section being indicated by the line 3—3 on said Fig. 2.

Of the printing press proper it will be sufficient to note the bed 1 which is the part that holds the form, and the disk 2 over 70 which the inking device passes in its travel from the fountain (not shown) to such form. Such device comprises essentially a series of composition rolls 3, 4 and 5, of familiar construction, which are supported at 75 their respective ends by arms 6 and 7 mov- ably mounted in an oscillatory frame 8, springs (not shown) being provided in con- nection with said arms to retain such rolls in more or less close contact with the surface 80 across which they travel. The forward roll 5 has the ends of its spindle 5^a directly jour- naled in arms 7, while the two following rolls 3 and 4 have the ends of their spindles 3^a and 4^a journaled in a saddle 11 that is 85 pivotally attached to the outer ends of the corresponding arms 6.

In moving from their uppermost position, shown in dotted outline in Fig. 1, down- 90 wardly across the disk 2, the aforesaid rolls 95 3, 4 and 5 directly contact with said disk under the pressure of the springs in the frames 8, there being of course one such frame on each side of the bed 1. However, in passing across the form mounted on the 95 front face of the bed 1, it is desirable, as previously explained, that the degree of pressure under which said rolls contact with the printing elements composing the form should be regulated, and to this end I pro- 100 vide in the present construction separate steel tracks 12, one on each side of said bed, wherewith the exposed metal ends of the rolls are adapted to contact, it being under- 105 stood that these tracks project slightly be- yond the face of the form when mounted in the bed so as to make up the difference due to the thickness of the layer of composition material that forms the body of the rolls. The upper ends 13 of the tracks are angu- 110

larly related to the main portions thereof so that the rolls may pass readily onto the track as they leave the disk 2.

Particular attention is directed to the means whereby these tracks 12 are secured to the bed 1. As shown in detail in Figs. 2 and 3, each such track is provided on its inner edge with two longitudinally spaced slots 14 that are laterally recessed or counter-bored on the outwardly directed face of such track to provide a recess 15 adapted to take an eccentric washer 16 rotatably mounted on a set bolt 17 that passes through such slot proper, and has threaded engagement (see Fig. 2) in the bed 1. Said washer 16 is provided with a flange 18 that covers over the recess 15 and is formed with a cylindrical portion having a series of radial apertures 19 and with a beveled portion having a series of graduations 20. Said flange 18, it will be observed, is concentric with the axis of set bolt 17, the head 21 of the latter bearing on the cylindrical portion of the washer, so that, upon tightening said bolt the flange 25 of the washer will be firmly clamped against the adjacent side face of the track 12. It will further be observed that there is a fixed setting mark or line 22 at a convenient point on the side face of the track adjacent the flange 18 of the washer, wherewith the successive graduations on such flange may be brought into register, also that such graduations are numbered consecutively, in order to indicate the amount of rotation which 35 may be given the washer for the purpose now to be set forth.

In use, assuming the set bolts 17 to have been loosened, the eccentric washers 16 may be rotated by inserting a pin in one of the holes 19, from the zero position shown in Fig. 3, in which the tracks are retracted as far as possible, to an angular position whereby said tracks are forced outwardly any desired distance up to the maximum throw of 45 such eccentric washers. When adjusted to desired position, the tracks are then securely held in place by tightening up set bolts 17, as will be readily understood. By means of the graduations on the beveled flange of the 50 washers, the amount of the adjustment thus secured may be closely figured, such graduations being calibrated with respect to the throw of the eccentric body of the washer proper. The tracks being made of steel instead of cast iron, as is the case where they 55 are formed integral with the bed 1 of the press, are of course extremely durable and show very little wear even after long and hard usage; while by mounting them in the 60 adjustable fashion described, they may be located throughout their length in accurate spaced relation to the face of the bed or form mounted therein, in order to secure proper

contacting pressure of the inking rolls with such form, even though the latter may have 65 shrunk so as to be of less diameter than when new.

Other modes of applying the principle of my invention may be employed instead of the one explained, change being made as regards the mechanism herein disclosed, provided the means stated by any of the following claims or the equivalent of such 70 stated means be employed.

I therefore particularly point out and distinctly claim as my invention:—

1. In a platen printing press, the combination with the bed, ink-distributing disk and composition rolls adapted to pass over said bed and disk; of separate steel tracks located one on each side of said bed and adapted to engage the ends of said rolls, each such track having a plurality of transverse slots formed in its rear edge, such slots being counter-bored to present open recesses substantially coextensive therewith; bolts threaded in the bed and adapted to receive such slots for securing the tracks to the latter; and washers rotatably mounted on said bolts and having eccentric portions disposed to lie in such recesses and engage with the inner ends thereof, whereby said track may be adjusted transversely of said bolts by rotating said washers, said bolts being adapted to press said washers against said tracks and thus clamp the same to the bed in such adjusted position.

2. In a platen printing press, the combination with the bed, ink-distributing disk and composition rolls adapted to pass over said bed and disk; of separate steel tracks located one on each side of said bed and adapted to engage the ends of said rolls, each such track having a plurality of transverse slots formed in its rear edge, such slots being counter-bored to present open recesses substantially coextensive therewith; bolts threaded in the bed and adapted to receive such slots for securing the tracks to the latter; and washers rotatably mounted on said bolts and having eccentric portions disposed to lie in such recesses and engage with the inner ends thereof, whereby said track may be adjusted transversely of said bolts by rotating said washers, said washers being also formed 115 with flanges overlying such recesses and provided with graduations adapted to indicate the position of said track and said bolts being adapted to press said washers with their flanges against said tracks and thus clamp the same to the bed in such adjusted position.

Signed by me this 20th day of January, 1921.

RALPH S. TYLER.
